HINGE ASSEMBLY

Louis Casper, Richmond Hill, N. Y.

Application April 18, 1938, Serial No. 202,647

7 Claims. (Cl. 296—44)

My invention relates to a hinge assembly for a door and door frame or pillar in connection therewith. Said hinge assembly being simple in construction and inexpensive of manufacture. The hinge assembly is applicable for doors on automobiles, aeroplanes and like vehicles.

This invention is also applicable for refrigerator doors, and for other applications where an especially trim appearing and pinch proof hinge assembly is desirable.

An object of this invention is to provide a hinge assembly for automobiles and like vehicles that has no projections or ears on the outside of the automobile body.

A further object of this invention is to provide a hinge assembly that eliminates an open space between the door and the door frame or pillar when said door is in open position, said open space being common to doors that are hung by ordinary types of hinges.

A further object is to provide a hinge assembly that enables the rapid and efficient hanging of the door incident to the assembly of an automobile body. Means are also provided for the easy removal of the door from the door frame or pillar support.

A further object is to provide a hinge assembly for a door eliminating the hazard of sag of said door or loosening of the same upon the bearings thereof. The hinge assembly furthermore eliminates the hazard of finger pinching in so far as the hinge assembly is concerned.

A further object is to provide a hinge assembly enabling the hanging of a door upon a door frame or pillar support without the need of screws, rivets, bolts or like securing means in the process of actually hanging the door.

The hinge assembly is divided between the door proper and the door frame or pillar. Secured to the door are two or more ball bearing bars which project beyond the edge of said door. The aforesaid bars terminate in an oval ball. Secured to the wall of the side of a car body is a bracket which is preferably welded to the car body. Upon this bracket socket bearings are provided into which the oval ball of said ball bearing bars are seated. Metal blocks, each having a bowl socket, are placed in position over said oval balls which serve to secure said oval balls in position in said bracket sockets. Said blocks are secured by block mountings snugly fitted in space provided and over said metal blocks.

In further description of the invention reference is had in the accompanying drawings, in

which Fig. 1 is a section of the side of a car body showing a door in partly open position.

Fig. 1a is a sectional plan view of the door support and the car door, said door swung in open position; said figure showing the close relation of the arcuate hinging edge of the door with the corresponding arcuate edge of the door pillar support.

Fig. 1b is similar to Fig. 1a showing the car door in closed position.

Fig. 1c is a perspective sectional view of a car body and a door showing the close relation of the arcuate hinging edge of the door with the arcuate edge of the door pillar.

15. Fig. 2 is a section of the door and door frame, top view.

Fig. 3 is a section of the door edge that faces the door frame and shows the door in open position.

20. Fig. 4 is a side view of the door partly in section.

Fig. 5 is a section taken on a line 5—5 of Fig. 2.

Fig. 6 is a section taken on a line 6—6 of Fig. 4.

Fig. 7 is a modification showing a thrust form of bearing.

Fig. 8 is also a modification showing another form of ball bearing.

Referring to the figures, the numeral 1 is a door, 2 is the door frame of the car, 3 is a bracket which is preferably welded to the body of the car, said car body also carrying an upright post 4 which is the usual construction of automobile bodies. 4a is the inner wall of the car body adjacent to the upright post 4.

30 On the bracket 3 are shown three oval shaped openings 7 through which the ball bearing bars are inserted.

Referring to Fig. 5 which shows the edge of the door frame 2 that faces the hinging edge of the door. Upon the edge of said door frame there are square shaped apertures 8. Below said apertures are slots 10 in which the ball bearing bars 13 swing. Each of said slots is provided with a stop member 11 which limits the swing of the bars 13 and consequently confining the opening of the door 1 within a certain defined limit.

40 Referring to Fig. 4 which shows in section the door 1 resting in closed position upon its hinged support on the car body.

The ball bearing bars 13 are secured to the door preferably by welding and project outward from the edge of the door 1. The oval ball 13

of said bar 13 rests in the socket bowl of the bracket 3.

The oval ball 13' is further secured in position by means of the upper bearing block 6, said block having a socket bearing which conforms to and is set in position over the ball 13' of the bar 13.

To secure the socket bearing block 6 in position over the ball 13', filler blocks 8 and 9 are snugly fitted into the space provided as shown in Fig. 4. A filler block 8 is first inserted through the opening 5 in the space provided for it directly over the upper bearing block 6. Another block 8 is fitted over the first block 8 in the space provided, said block being also inserted through the opening 5. Finally the block 9 is fitted into the remaining space provided in the opening 5, said block 9 being allowed to project slightly beyond the surface level of the door frame 2. The slight protuberance of the filler block 9 provides a cushion for the car door 1, the block 9 being preferably made of resilient rubber.

An important feature of the invention is in the fact that the edge of the door frame has an arcuate outline being convex in contour and which conforms precisely to the concave contour of the edge of the door 1 facing said door frame edge. Said arrangement enables the door to swing in a close air space relation with respect to said door frame edge. The movement of the hinge arrangement of the door is uniform, and said hinge arrangement is of similar appearance when viewed from either the inside or from the outside of the car.

The method of hanging the door 1 is as follows: The door is lifted up to a height sufficient for the oval balls 13' of the bars 13 to be on a line with the rounded openings 7. The door is then pushed against the door frame 2 until each of the balls 13' are directly over the socket bowls on the bracket 3. The door is then permitted to drop downward and said balls 13' will rest in the respective socket bowls aforesaid. The metal blocks 6 are then placed through the apertures 5 over the balls 13', the socket bowls of each block being placed in position over said balls 13'. The filler blocks 8 are then inserted through the apertures 5 and placed in position over the blocks 6, then finally the cushion blocks 9 which are preferably of rubber are placed in position as shown in Fig. 4.

To remove the door the three cushion blocks 9 are taken out. The filler blocks 8 are then removed, and finally a tool is inserted in the hole 6' by which means the bearing block 6 is lifted up to the opening or aperture 5 and withdrawn from the frame of the car body. The above description applies similarly to the three openings or apertures 5.

The door 1 is then lifted clear of the socket bowl bearings and said door is then pulled outward thus bringing the balls 13' out through the apertures 7 and clear of the door frame 2.

The numeral 16 is a reinforcement bracket to which the ball bearing brackets are welded.

The numeral 18 is a V-shaped space opening, said opening facilitates the hanging of the door 1.

Referring to Fig. 7 which shows a modified thrust bearing in lieu of the ball 13' and its companion socket bearing bowl. The bar 13 has a bearing 13b which rests in the thrust bearing 13a, said thrust bearing being integral to the bar 13.

In Fig. 7 the bracket 3 is similar to the bracket 3 in Fig. 1. The rounded opening 7 is also provided to permit the entrance of the 75

bar 13 and into position as shown. The metal block 6 is placed through the aperture 5 and over the bar 13 and the bearing 13b.

Referring to Fig. 8 which is a further modification of the bearing arrangement in lieu of the bar supporting arrangement shown in Fig. 4. The bar 13 terminates in a bearing 13a which rests in thrust bearing 15' said bearing being integral to the bracket 3.

10 A thrust bearing 15' is affixed in position through the aperture over the end section 13a of the bar 13. The filler blocks 8 and 9 are placed in position over the bearing 15' in a manner similar to that described of the ball 13' arrangement.

15 It will be seen that this invention is capable of some modification other than that described without departing from the spirit of the invention. The invention furthermore permits of considerable tolerances in fitting the door to the door frame or other door support in that the individual bars 13 may be slightly lengthened or shortened as the case may be to precisely rest in the respective bearing bowls of the blocks in bracket 3. Likewise the bearing blocks in the bracket 3 may be separately varied in inward or outward direction to afford precise seating of the spheroidal shaped ends 13' of the bars 13.

20 Now having described my invention what I claim is—

25 1. In a hinge assembly of the class described including a plurality of bars secured to a door, said bars projecting outward from the hinging edge of said door, the ends of said bars formed to seat into respective bearings, said bearings integral to a door frame or like door support, demountable bearing means mounted above said bar bearings, blocking means for retaining said demountable bearing means in position with respect to said seating of said bars, said bars movable in respective slots in said door frame, said bar movement in said slots incident to the opening and closing of said door, and an aperture above each of said slots enabling the insertion 30 of said bars within said slots and thereby enabling the mounting of the respective ends of said bars in the bearings thereof; a second aperture for each of said bar bearings in said door frame whereby said blocking means may be inserted into position above the bearing means aforesaid.

35 2. In a hinge assembly of the class described including a plurality of bars secured to a door, said bars projecting outward from said door and in position for insertion into respective slots affixed in the arcuate section of a door frame or like support, the ends of said bars terminating in a pintle, said pintle seated in respective lower thrust bearings integral to said door support, an upper thrust bearing mounted above said lower thrust bearing, said upper bearing holding said pintle in position with respect to said lower bearing, blocking means for holding said upper bearing in position; the arcuate section of said 40 door support conforming to the arcuate hinging edge of said door, said seated bars swinging in a slot affixed in said door support, and an aperture above said slots enabling the entrance of said bars into said slots and the seating thereof in said bearings incident to the hanging of said door upon the door support aforesaid.

45 3. In a hinge assembly of the class described including a plurality of bars integral to a door, each of said bars terminating in a bearing pin, said pins seated in respective thrust bearings,

said bearings integral to a door frame or like door support, each of said bars movable in respective slots in said door support, an aperture above each of said slots corresponding to said bars, said aperture permitting each of said bearing pins to be seated in said respective bearings incident to the hanging of said door upon said door support; and a removable metal mounting over said pins, and removable filler blocks of resilient material over said mountings, said filler blocks also serving the purpose of a cushion for said door upon the closing thereof the hinging edge of said door having an arcuate contour shaping, said shaping corresponding to like arcuate shaping of the section of said door support in the swinging area of said hinging door edge; and stopping means in said hinge assembly limiting the extent of the opening of the door aforesaid.

4. In a hinge assembly including a door pillar, said door pillar having a curvilinear edge, a door having a like curvilinear edge at its hinging side and cooperating with said curvilinear edge on said door pillar, a hinging bar or bars integrally secured to said door and projecting outwardly therefrom upon the mounting of said door upon said door pillar, said hinging bars being projected through corresponding open slots in said curvilinear edge of said door pillar, said bars resting upon corresponding bearing means mounted behind said curvilinear edge of said door pillar, and blocking means mounted contiguous to each of said bars and bar bearing means for the purpose of securing said bars in secure position upon said bearing means, said blocking means including a metal mounting over said bearing means, filler blocks of resilient material insertable over said mounting, said filler blocks after insertion thereof serving as a holding medium for said metal mountings and also serving as a cushion for said door upon the closing thereof.

5. In a hinge assembly of the class described including a plurality of bars secured to a door, said bars projecting outward from the hinging

- edge of said door, each of said bars terminating into a spheroidal shaped head, said heads seated into respective socket bearings, said bearings integral to a door frame or like door support, an upper bearing block above each of said heads, said respective upper bearing blocks held in position by filler blocks of resilient material fitted within a space inside said door frame or like door support, said filler blocks acting as securing means for said bearing blocks and also as a cushion for said door upon the closing thereof, each of said bars movable in respective slots in said door frame incident to the opening and closing of the door aforesaid.
- 15 6. The structure as set forth in claim 5, and an opening above each of said slots enabling the insertion of said bars within said slots, and apertures in said door frame for the insertion into position respectively of said upper bearing block and filler blocks aforesaid.
- 20 7. In a hinge assembly of the class described including a plurality of bars secured to a door, said bars projecting outward from said door and in positions for insertion into respective slots 25 affixed in the arcuate edge of a door frame or like door support, the ends of said bars seated in respective socket bearings integral to said door support and behind said slots, a removable metal block mounting over said respective bar ends and removable filler blocks of resilient material insertable over said metal block mounting; the arcuate section of said door support conforming to the arcuate hinging of said door, enabling said door edge to swing in the arcuate area section of said door support, and an aperture 30 above said slots enabling the seating of said bar ends in said bearings incident to the hanging of said door upon said door support, and a second aperture in said door support for the purpose of entrance for said filler blocks, said filler blocks 35 also serving the purpose of a cushion for said door upon the opening and closing thereof.

LOUIS CASPER.
